SPARK-PLUG AND METHOD OF MANUFACTURING THE SAME.

1,228,767.

Specification of Letters Patent.

Patented June 5, 1917.

Application filed March 17, 1917. Serial No. 155,463.

To all whom it may concern:

Be it known that I, FREDERICK M. FURBER, a citizen of the United States, residing at Revere, in the county of Suffolk and State of Massachusetts, have invented certain Improvements in Spark-Plugs and Methods of Manufacturing the Same, of which the following description, in connection with the accompanying drawings, is a specification, 10 like reference characters on the drawings indicating like parts in the several figures.

This invention relates to spark plugs and to methods of manufacturing spark plugs. The exceedingly keen competition which 15 has arisen in recent years in the spark plug industry has made the adoption of economical constructions and methods of manufacture of these devices a practical necessity to the maintenance of a successful business in 20 this line. At the same time the users of spark plugs have become more exacting in their requirements and are demanding a spark plug of a much sturdier and more substantial construction than has heretofore 25 been required. The trade is also demanding a spark plug that is very reliable and is substantially gas tight under operating conditions; and these changes in the demands of the trade have, of course, complicated the 30 problems presented to the spark plug manufacturers. It will readily be appreciated by those skilled in this art that the chief manufacturing difficulty resides in the assembling of the insulator in the body or shell of the 35 plug. This difficulty arises primarily from the fact that the insulators are relatively fragile and that they vary greatly in dimensions. Most of these insulators are made of porcelain which, of course, warps and becomes distorted in the baking operations, 40 thus producing extraordinary variations in dimensions which require the use of gaskets or similar means to accommodate these variations and prevent the application of excessive pressure to relatively small areas of 45 the insulator. Even then these variations render it difficult to apply the pressure necessary to produce a gas tight joint between the insulators and the shells without breaking the insulators.

The present invention has for its general object to devise a spark plug that will satisfy the requirements of the trade and at the same time to devise a plug construction and 55 a method of manufacturing it which will solve the problems presented to the manu-

facturer. Stated more specifically, the invention aims to devise a sturdy, substantial and reliable spark plug which can be economically manufactured and which will be 60 so constructed that much of the skill and exactness required in manufacturing spark plug constructions heretofore proposed will be eliminated.

The invention is particularly concerned 65 with the mounting of the insulator in the shell or body of the plug.

The invention will be readily understood from the following description, reference being made to the accompanying drawings, 70 in which:

Figure 1 is a view in perspective of a spark plug embodying the invention;

Fig. 2 is a vertical cross sectional view of the plug shown in Fig. 1;

Fig. 3 is a side elevation of a part of the 75 spark plug, showing a step in the process of manufacture;

Fig. 4 is a fragmentary cross sectional view, on a large scale, of a part of the spark 80 plug shown in Figs. 1 and 2;

Fig. 5 is a cross sectional view, partly in elevation, showing the spark plug and one of the tools that operates on it;

Fig. 6 is a view, partly in vertical cross 85 section and partly in side elevation, showing the apparatus which distorts the shell to clamp the insulator therein; and

Fig. 7 is a cross sectional view of a part 90 of a modified form of plug.

The plug shown comprises a shell or body 2, which may be made out of cold rolled stock of hexagonal cross section, the lower part of this shell or body being turned down to form a shank which is screw threaded to 95 adapt it to be secured in an engine cylinder. The shell is drilled to form a bore therethrough and is counterbored from its outer end, that is, the end which projects out of the engine cylinder when the plug is in use, 100 to form an internal shoulder or seat 4. An insulator 6 is positioned in the bore of the shell 2 and is provided with a circumferential enlargement 7, the ends of which form upper and lower shoulders 8 and 9, respectively. The shoulder 4 in the shell forms a seat for the lower shoulder 9 of the insulator 6, a gasket 10 being interposed between this seat and the shoulder.

The insulator is held in the shell by means 110 of an annular flange 12 formed integrally with the shell 2 at its outer end and turned

inwardly over the upper shoulder 8 of the insulator into position to clamp the enlargement 7 of the insulator securely against the seat 4. Preferably a gasket 5 is interposed between the shoulder 8 and the flange 12 to protect the shoulder. It will be noted that the enlargement 7 of the insulator is so much smaller in diameter than the bore of the shell that a lateral clearance 10 is provided between the shell and the peripheral surface of the enlargement 7. The insulator thus is secured in the shell solely by the parts that engage the shoulders 8 and 9.

15 According to the preferred method of manufacturing the plug, the insulator and shell are made in the usual way but the shell 2 is provided with an annular flange 12 at its outer end, as shown in Fig. 6. The gaskets 10 and 14 are then placed on the shoulders 9 and 8, respectively, and the shell is inserted in the plug in its normal or operative position. The shell 2 then is supported in an upright position in a die 16, as shown 20 in Fig. 6, and another die or swaging tool is employed to turn the flange 12 inwardly or crimp it over the shoulder 8. It will be noted that while the flange 12 is relatively thin as compared with the main body of the 25 shell, it is thicker than the flange usually employed in spark plugs of this general construction. Such flanges heretofore have been made very thin so that they could be crimped readily over the upper shoulder of 30 the insulator; and according to the processes heretofore followed in the assembling plugs of this type the flange has been crimped or turned over at a single operation. In some instances the flanges are heated sufficiently 35 to render them relatively plastic so that they can be distorted more readily. In all of these cases, however, difficulty has been encountered in handling insulators in which there is an appreciable variation in the 40 height of the enlargement at different points circumferentially thereof. It will readily be appreciated that if the flange 12 of the insulator were turned in by a bell-shaped die, of the character usually employed, or 45 by spinning, and the enlargement 7 were appreciably higher on one side than the other, the high side would be subjected to much greater pressure than the low side; and the probable result would be either to break the 50 insulator or else to leave the flange in such a condition that the plug would not be gas tight on the low side of the insulator.

According to the present invention the flange is turned in, or crimped, in such a 60 manner that it clamps the enlargement of the insulator against the seat 4 with a pressure which is substantially uniform at all points circumferentially thereof.

Referring now to Figs. 3 and 6, it will be 65 seen that the upper die comprises two mem-

bers 18 arranged to operate on the flange 12 at diametrically opposite points, (using the term "points," not in its geometrical sense, but rather in the sense of designating a relatively small area). The members 18 are 70 both secured pivotally to a yoke 20 and are held in a properly spaced relation to each other by guides 22. These upper die members 18 are reciprocated toward and from the lower die 16 in a direction parallel to the axis of the spark plug. The mechanism by which this movement is produced, may comprise a plunger 24 connected to the yoke 20 by a pivot 26, which is mounted in the yoke and passes through a slot 28 in the lower end of the plunger. A stiff coiled spring 30 surrounds the plunger 24 and bears at one end against the yoke 20 and at its opposite end against a head 32 with which the plunger is provided. A power driven mechanism of 75 some kind may be employed to act through the head 32 to apply pressure to the upper die, and the arrangement just described equalizes this pressure between the two die members 18 which act directly on the 80 flange 12.

As clearly shown in Figs. 3 and 6, the lower ends of the two die members 18 are shaped to force the part of the flange which they engaged inwardly over the upper shoulder 8. Preferably these flange-engaging parts of the dies are notched to provide tooth-like projections A Fig. 3 with spaces, as B, between them. Consequently, when the upper die is forced toward the lower die, 95 these members will force the parts of the flange which they engage inwardly over the shoulder 8 into the crimped or turned-in position in which they are shown in Figs. 1 and 4. When the upper die 18 recedes, the 100 plug is turned or indexed into position for the next downward stroke of the die; and this operation is continued until the points of operation of the upper die have been transferred completely around the flange 105 and the entire flange has been crimped over the upper shoulder of the insulator. It sometimes is preferable to operate twice 110 around the flange in this manner.

It will now be understood that according 115 to this process only a small part of the flange is distorted at one time and that by operating on the flange at diametrically opposed points and equalizing the pressure applied to these points, a very great pressure 120 can be applied to each point of operation so that the firm clamping of the insulator in the shell is insured. At the same time, if the enlargement 7 of the insulator is higher on one side than the other, which practically 125 always is the case, the flange is turned over against the upper shoulder at both sides with substantially the same pressure, notwithstanding these variations in height. For the sake of economy in manufacture, it is pref- 130

- erable to perform the crimping operation while the parts are at substantially normal temperatures and thus avoid the expense and apparatus required to heat the flange. 5 This advantage is obtained by the process above described. The notching of the lower ends of the two die members 18, as shown, allows the metal to flow laterally in opposite direction from the points at which the greatest distortion of the metal of the flange is taking place and thus avoids the danger of cracking the flange which otherwise might prove troublesome in attempting to crimp it while in a cold condition. 10
- 15 This process produces a flange that varies in thickness and also in density at successive points circumferentially of the flange and this construction of the flange is of advantage in stiffening it and enabling it better to 20 resist any tendency to spring back or return toward its original position. This construction, however, is not regarded as absolutely essential in the finished plug provided the flange is made of sufficient thickness and 25 these corrugations may be turned off if desired after the plug has been completed. The variation in density of the flange will still be present, however, as will also the variation in density lengthwise of the flange 30 due to its being turned inwardly.
- Preferably the gaskets 10 and 14 consist simply of washers made of some soft metal, such as copper. This material protects the shoulders of the insulator from injury 35 which they might otherwise sustain by contact with the harder metal of which the shell is made, and at the same time it does not yield sufficiently to relieve the firm clamping pressure which the flange 12 exerts on the 40 upper shoulder 8. It is found in practice that satisfactory results are obtained by applying to the upper die a pressure of approximately 2,000 lbs., in performing the crimping operation. This pressure is equalized between the two die members 18 so that 45 substantially 1,000 lbs. are applied to each member at each operative stroke of the plunger. It is obvious that the upper die member could be arranged to operate simultaneously at more than two points on the flange, 50 if desired, but such an arrangement would require the application of considerable more pressure to the die mechanism in order to apply the same amount of pressure to each 55 point at which the distortion or crimping of the flange is taking place. Accordingly, I prefer to arrange the apparatus as shown. But whether the crimping action takes place simultaneously at two or more points, it is 60 preferable to have these points spaced apart at substantially uniform distances circumferentially of the flange, and to equalize the pressure used so that the pressure applied at each point will be substantially the same as 65 that applied at any other point. This ar-
- angement is of material advantage in preventing the breakage of the insulators in case the enlargement of the shoulder is appreciably higher on one side than on the other and also in producing a gas tight joint 70 between the insulator and the shell. 75
- In making spark plugs of this general type according to the methods heretofore practised, the use of a relatively soft gasket between the lower shoulder 9 and the seat 4 has been relied upon to produce a gas tight joint because it was found practically impossible to make a gas tight joint at the upper end of the enlargement 7 and still use the firmer gasket which seemed advantageous at this point. The present method, however, produces a gas tight joint at the upper end of the enlargement 7 notwithstanding substantial variations in the height of this enlargement at this point circumferentially thereof. This result is produced by crimping only relatively small parts of the flange 12 at a time and equalizing the pressure between the points at which the crimping operation is taking place, so that 80 when this operation is completed, the flange is shaped to conform the upper gasket to the contour of the upper shoulder 8 and maintains a substantially uniform pressure on said gasket at all points circumferentially 85 thereof notwithstanding the variations in the height of said enlargement. 90
- If desired the flange 12 may be grooved internally, as indicated at 38, Fig. 7, to provide annular grooves and ribs on its inner surface which enable this part better to grip the upper gasket 14 during the crimping operation, and to exert a better holding action on the gasket thereafter. This construction however is not usually necessary. 100 105
- As above stated, a lateral clearance is provided between the bore of the shell and the peripheral surface of the enlargement 7 so that, while there may be a contact between these surfaces at one or more points, 110 there is no possibility of the shell exerting sufficient pressure on the insulator laterally thereof to crush the insulator. 115
- The construction of the plug herein shown and described is such that any ordinary and reasonable variations in the dimensions of the parts of which it is made up do not interfere with the production of a satisfactory plug. It will be evident from an inspection of Figs. 2 and 6 that any reasonable 120 variation in the depth of the counterbore of the plug, in the thickness of the gaskets 10 and 14, and in the height of the enlargements 7 will not be sufficient to prevent the flange from being crimped into clamping 125 relationship to the insulator as above described. If, however, due to unusual conditions these variations seem likely to cause trouble, this difficulty can be obviated by making the flange 12 long enough to take 130

care of extreme variations and then turning off the superfluous length of this flange just before the flange crimping operation is performed. Fig. 5 shows at 34 an end cutting tool in the act of reducing the length of the flange 12, a gage 36 being provided to enter the counterbore of the plug and engage the upper gasket 14 thus stopping the reducing action when the flange has been 10 cut down to substantially a predetermined height above the shoulder 8 and above the gasket 14.

It is obvious that practically all the operations in the manufacture of the shell and 15 in the mounting of the insulator in the shell can be performed by automatic machinery and that much of the exactness heretofore required in the manufacture of these parts is eliminated by this invention. The cost 20 of manufacture of a plug according to this construction and by this method is materially reduced. Furthermore it has been found from actual practice that this invention solves the difficulties heretofore experienced in producing a gas tight joint 25 between the insulators and the shells, even when the insulators are very badly warped, and that an unusually small percentage of the insulators are broken in the process of 30 assembling the plugs.

What is claimed as new is:

1. A spark plug comprising a shell having a bore formed therethrough, an insulator positioned in said bore and having a 35 circumferential enlargement with shoulders at the opposite ends of said enlargement, a seat in said shell supporting one of said shoulders, and a corrugated flange at the outer end of said shell turned inwardly over the 40 other shoulder of said insulator and clamping the insulator in the shell.

2. A spark plug comprising a shell having a bore formed therethrough, an insulator positioned in said bore and having a circumferential enlargement with shoulders at the opposite ends of said enlargement, a seat in said shell supporting one of said shoulders, and a flange at the outer end of said shell turned inwardly over the other 50 shoulder of said insulator to secure the insulator in the shell, said flange having radially extending ribs formed therein.

3. A spark plug comprising a shell having a bore formed therethrough, an insulator positioned in said bore and having a circumferential enlargement with shoulders at the opposite ends of said enlargement, a seat in said shell supporting one of said shoulders, and a flange at the outer end of said shell turned inwardly over the other shoulder of said insulator to secure the insulator in the shell, said flange having radially extending ribs in its outer face and annular ribs in its inner face.

4. A spark plug comprising a shell hav-

ing a bore formed therethrough, an insulator positioned in said bore and having a circumferential enlargement with shoulders at the opposite ends of said enlargement, a seat in said shell supporting one of said shoulders, and a flange at the outer end of said shell turned inwardly over the other shoulder of said insulator to secure the insulator in the shell, said flange varying in density at successive points circumferentially thereof. 70

5. A spark plug comprising a shell having a bore formed therethrough, an insulator positioned in said bore and having a circumferential enlargement with shoulders at the opposite ends of said enlargement, a seat in said shell supporting one of said shoulders, and a flange at the outer end of said shell turned inwardly over the other shoulder of said insulator to secure the insulator in the shell, successive portions of said flange both circumferentially and longitudinally thereof being of different densities. 80

6. A spark plug comprising a shell having a bore formed therethrough, an insulator positioned in said bore and having a circumferential enlargement with shoulders at the opposite ends of said enlargement, a seat in said shell supporting one of said shoulders, and a flange at the outer end of said shell turned inwardly over the other shoulder of said insulator to secure the insulator in the shell, said flange varying substantially in thickness at successive points 90 circumferentially thereof. 95

7. A spark plug comprising a shell having a bore formed therethrough, an insulator positioned in said bore and having a circumferential enlargement with shoulders at the opposite ends of said enlargement, a seat in said shell supporting one of said shoulders, the distance between said shoulders varying appreciably at different points circumferentially of said enlargement, and an annular flange at the outer end of said shell turned inwardly over the other shoulder and exerting a substantially uniform pressure on said enlargement at all points circumferentially thereof. 105 110

8. A spark plug comprising a shell having a bore formed therethrough, an insulator positioned in said bore and having a circumferential enlargement with upper and lower shoulders, respectively, at the opposite ends of said enlargement, a seat in said shell supporting the lower of said shoulders, and a flange at the outer end of said shell, integral with the shell, and turned inwardly over the upper shoulder, said enlargement varying appreciably in height at different points circumferentially thereof, and said flange being shaped to exert a substantially uniform pressure on said upper shoulder at all points circumferentially 115 120 125 130

- thereof and thereby to clamp said enlargement against said seat.
9. That improvement in the method of securing an insulator having a circumferential enlargement with upper and lower shoulders, respectively, at the opposite ends of said enlargement, in a spark plug shell having an internal seat for the lower of said shoulders, which consists in forming a flange in the outer end of said shell, placing said insulator in the shell, and turning said flange in progressively over the upper shoulder of the insulator into clamping relationship therewith. 70
10. That improvement in the method of securing an insulator having a circumferential enlargement with upper and lower shoulders, respectively at the opposite ends of said enlargement, in a spark plug shell having an internal seat for the lower of said shoulders, which consists in forming a flange in the outer end of said shell, placing said insulator in the shell, and turning said flange in progressively over the upper shoulder of the insulator into clamping relationship therewith. 75
11. That improvement in the method of securing an insulator having a circumferential enlargement with upper and lower shoulders, respectively at the opposite ends of said enlargement, in a spark plug shell having an internal seat for the lower of said shoulders, which consists in forming a flange in the outer end of said shell, placing said insulator in the shell, and acting on a relatively small part only of said flange at a time, and with a substantial predetermined force, to force it inwardly over said upper shoulder into position to clamp said enlargement against said seat. 80
12. That improvement in the method of securing an insulator having a circumferential enlargement with upper and lower shoulders, respectively, at the opposite ends of said enlargement, in a spark plug shell having an internal seat for the lower of said shoulders, which consists in forming a flange in the outer end of said shell, placing said insulator in the shell, and turning said flange inwardly over said upper shoulder in such a manner that the flange will exert substantially a uniform pressure on said upper shoulder at all points circumferentially thereof notwithstanding variations in the height of the enlargement. 85
13. That improvement in the method of securing an insulator having a circumferential enlargement with upper and lower shoulders, respectively, at the opposite ends of said enlargement, in a spark plug shell having an internal seat for the lower of said shoulders, which consists in forming a flange in the outer end of said shell, placing said insulator in the shell, and turning said flange inwardly over said upper shoulder while the flange is at substantially normal temperature in such a manner that the flange will exert substantially a uniform pressure on said upper shoulder at all points circumferentially thereof notwithstanding variations in the height of the enlargement. 90
14. That improvement in the method of securing an insulator having a circumferential enlargement with upper and lower shoulders, respectively, at the opposite ends of said enlargement, in a spark plug shell having an internal seat for the lower of said shoulders, which consists in forming said shell with a relatively thin annular flange at its outer end, inserting said insulator in the shell, and turning said flange in over the upper shoulder progressively by operating on a small part only of the flange at a time and allowing part of the metal of the flange to flow laterally away from each point of operation. 95
15. That improvement in the method of securing an insulator having a circumferential enlargement with upper and lower shoulders, respectively, at the opposite ends of said enlargement, in a spark plug shell having an internal seat for the lower of said shoulders, which consists in forming said shell with a relatively thin annular flange at its outer end, inserting said insulator in the shell, crimping said flange over said upper shoulder into clamping relationship therewith while the flange is at substantially normal temperature by operating on said flange at points spaced apart at substantially equal distances circumferentially of the flange and applying substantially the same pressure to each of said points, and transferring said points of operation around the flange until said crimping operation is completed. 100
16. That improvement in the method of securing an insulator having a circumferential enlargement with upper and lower shoulders, respectively, at the opposite ends of said enlargement, in a spark plug shell having an internal seat for the lower of said shoulders, which consists in forming said shell with a relatively thin annular flange at its outer end, inserting said insulator in the shell, and turning said flange over the upper shoulder progressively into clamping relationship therewith by operating on it simultaneously at substantially diametrically opposite points and equalizing the pressure applied to said points. 115
17. A spark plug comprising a shell having a bore formed therethrough, an insulator positioned in said bore and having a circumferential enlargement with upper and lower shoulders, respectively, at the opposite ends 120
18. A spark plug comprising a shell having a bore formed therethrough, an insulator positioned in said bore and having a circumferential enlargement with upper and lower shoulders, respectively, at the opposite ends 125
19. A spark plug comprising a shell having a bore formed therethrough, an insulator positioned in said bore and having a circumferential enlargement with upper and lower shoulders, respectively, at the opposite ends 130

of said enlargement, a seat in said shell supporting the lower of said shoulders, and a flange at the outer end of said shell turned inwardly over the upper shoulder, said enlargement varying appreciably in height at different points circumferentially thereof, and a gasket on said upper shoulder, said flange being shaped to conform said gasket

to said upper shoulder and to maintain a substantially uniform pressure on said 10 gasket at all points circumferentially thereof notwithstanding said variations in the height of said enlargement.

In testimony whereof I have signed my name to this specification.

FREDERICK M. FURBER.
